UNITED STATES PATENT OFFICE.

NOAH S. MOSLEY, OF FORT WORTH, TEXAS.

HEAD FOR HAMMERS AND OTHER TOOLS.

1,267,441.

Specification of Letters Patent.

Patented May 28, 1918.

Application filed July 16, 1917. Serial No. 180,695.

To all whom it may concern:

Be it known that I, NOAH S. MOSLEY, a citizen of the United States, residing at Fort Worth, in the county of Tarrant and State of Texas, have invented certain new and useful Improvements in Heads for Hammers and other Tools, of which the following is a specification.

My invention relates to heads for hammers, hatchets, axes, adzes, and the like, and the object is to provide heads for such tools which can be adjusted to handles and securely attached thereto and to provide means by which the handles are prevented from becoming loose in the heads and to provide means for tightening the handles in the heads. Other objects and advantages will be fully explained in the following description and the invention will be more particularly pointed out in the claims.

Reference is had to the accompanying drawings which form a part of this application.

Figure 1 is a side elevation of a hammer which is provided with the improvements. Fig. 2 is a vertical section of the head and a portion of the handle. Fig. 3 is an end view of the hammer with a part thereof shown in section. Fig. 4 is a side elevation of the dovetailed binder bar and a section of the strap. Fig. 5 is a side elevation of a hammer, showing a variation from the hammer shown in the previous views.

Similar characters of reference are used to indicate the same parts throughout the several views.

A hammer of ordinary type is shown in the drawings. The hammer has a head 1 and handle 2. The head 1 has an eye to receive the tapered end 3 of the handle. The handle is secured in the head 1 by a block or cross-stay 4 which is dovetailed into the head 1 and across the eye thereof. The end 3 is tapered so that it can be wedged into the head 1 which has an eye which conforms in contour to the tapered end 3. The end of the handle is slotted to receive the cross-stay 4. A screw 5 runs through the cross-stay 4 into the handle 2 and draws the handle toward the cross-stay and thus tightens the handle in the head. The handle does not extend flush with the outer edge of the cross-stay,—leaving space for the handle to be

tightened. A strap 6 is also used to aid in holding the handle and the head rigid with each other. The screw 5 may be run through the strap 6, as shown in Figs. 1 and 2, or the strap 6 may be used to bear against the screw 5, as shown in Fig. 5. In the forms shown in Figs. 1 to 4 inclusive, the strap 6 and the cross-stay 4 may be made rigid with each other by countersinking the strap in the cross-stay. In order that the strap 6 may not interfere with the handle 2, the strap may be countersunk in the walls of the head above and below the handle, as shown in Fig. 3. With such construction, the handle 2 will bear against the head at 7 so that the handle will be rigid with the head 1. The strap may be flush with the inner face of the eye in the head so that the handle may be tightened against the strap by means of the screw 5. When the stay is forced into place by the screw 5, it can be secured to the handle 2 by a small bolt 8.

It is apparent that the handle can be tightened in the head 2 if the handle should become loose. This can be done by turning the screw 5. The tapering form of the handle makes it feasible to tighten the handle. The end 9 of the handle may be trimmed off slightly and the slot in the handle for the cross-stay 4 may be made deeper to take up wear of the handle.

The improvements herein set forth are useful for the purposes above set forth and for many other purposes, as for securing the handles in picks, securing the cuffs on swing and double trees and on breast-yokes, and for securing the handles on other such tools as hoes and rakes.

What I claim is,—

1. A hammer comprising a head having a tapering eye, a handle having a tapering end fitted into said eye and projecting through said head, a cross-stay dovetailed in said head and in said handle, said handle having a slot for said cross-stay deeper than the cross-stay, a strap countersunk in the inner walls of said eye and in the face of said cross-stay, and a screw running through said strap and cross-stay and penetrating said handle for tightening said handle in said eye.

2. A hammer comprising a head having a tapering eye, a handle having a tapering

end fitted into said eye, a cross-stay for tightening said handle in said eye dovetailed in said head and said handle having a slot for said cross-stay, a strap countersunk in 5 said cross-stay and engaging the end of said handle and projecting through said eye, and a screw running through said strap and

cross-stay and into said handle and coöperating with said cross-stay, and means attaching said strap to said handle.

In testimony whereof, I set my hand this 2nd day of December, 1915.

19

NOAH S. MOSLEY.
